UNITED STATES PATENT OFFICE.

EDGAR W. ANTHONY, OF BOSTON, MASSACHUSETTS, ASSIGNOR TO THE SMITH & ANTHONY COMPANY, OF SAME PLACE.

DAMPER FOR HEATING STOVES OR FURNACES.

SPECIFICATION forming part of Letters Patent No. 547,235, dated October 1, 1895.

Application filed May 28, 1894. Serial No. 512,572. (No model.)

To all whom it may concern:

Be it known that I, EDGAR W. ANTHONY, a citizen of the United States, residing at Boston, in the county of Suffolk and State of Massachusetts, have invented a new and useful Improvement in Dampers for Heating Stoves or Furnaces, of which the following is a full, clear, and exact description, reference being had to the accompanying drawings, forming a part of this specification, in explaining its nature.

In most air-heating furnaces a pipe extends across the air-heating chamber from the radiator-shell to the pipe leading to the chimney. This pipe contains the passage connecting the combustion-chamber with the flue and also with the downtake. It is desirable that there be a damper in this pipe between the combustion-chamber and the chimney-pipe or downtake, where one is used and dampers have been so located; but their use has been objectionable, in that it has been difficult to secure them in such pipe because of its position, and it has been especially difficult to remove a worn out or disabled one and substitute therefor a new one. This was because the ordinary or old forms of damper and damper-hanger were used, and out of this grew another defect, and that was the escape of gas from the combustion-chamber about the hole through which the ordinary damper-operating rod or spindle extended, more or less gas thereby leaking into the air-heating chamber. My present invention overcomes both these objections. It affords a means by which the damper may be easily removed and replaced or another one substituted, and it prevents the leakage of gas into the air-heating chamber.

In the drawings, Figure 1 is a view in front elevation of the smoke-pipe and damper, a portion of the pipe being broken out to show the construction hereinafter described. Fig. 2 is a plan view thereof, representing the pipe as attached to the furnace or stove shell. Fig. 3 is a view in elevation of a furnace partly broken away, showing the attachment of my device to an ordinary furnace.

In carrying my invention into effect I prefer to use the pipe A, having a flange a, by which it is secured to the radiator and form-

ing the direct escape-passage a' from the combustion-chamber to the pipe leading to the chimney, and also having the downwardly-extending collar a², which receives the pipe forming the indirect passage or downtake. This pipe has at its forward end the damper B, which is secured in place by means of a pin b at its lower edge, which enters into a cup b' arranged to receive it, and a spindle b², preferably square and extending through a hole b³ in the casting and entering the square holes b⁴ in the damper, the said holes being in line with each other. This provides a short spindle, one that can be easily inserted into the holes of the damper.

To prevent the escape of gas about the spindle-hole there is cast about the hole and at a suitable distance from it an upwardly-extending wall c, and there is also cast with or attached to the pipe-casting, immediately about the opening necessary for the spindle, an inner wall c'. This, with the outer wall, forms an annular chamber c², which is filled with sand and into which the edge of the inverted cup c³, carried by the spindle, enters, (see Fig. 1,) and there is thus established a sand-joint around the spindle, through which gas cannot escape.

The spindle b² is held in place partly by its weight and partly by the means employed for turning it, which consists generally of the crank-arm c⁴ and a rod c⁵. The inner wall c', as I have stated, may be cast, or it may be formed by a threaded tube arranged to screw into the casting.

In Fig. 3 C is the air-chamber of the furnace and D is the downtake. I attach my damper to the casting A within the air-chamber C. It is necessary in this construction that the damper be secured to the casting A in such a manner that no passages are left by which gas might escape into the air-chamber C.

Having thus fully described my invention, I claim and desire to secure by Letters Patent of the United States—

1. In a heating stove or furnace, the casting A forming the direct escape-port and having the opening for the damper operating spindle and a chamber formed about said opening containing sand or similar material

and the damper B and damper spindle passing through said opening and having an inverted cup which enters into the sand or other material contained in the chamber, as and for 5 the purposes described.

2. In a heating stove or furnace, the combination of the casting A having the chamber c^3 formed by the walls $c\ c'$, as described and surrounding the damper spindle hole, with 10 the damper B having the sockets b^4 , the re-

movable spindle b^2 and the inverted cup c^3 carried by the spindle and entering the chamber c^2 and sand or similar material contained in said chamber to establish a joint in connection with the cup c^3 , as and for the purposes described. 15

EDGAR W. ANTHONY.
